UNITED STATES PATENT OFFICE

142,549

DESIGN FOR A CRUTCH GRIP

Frederick Fink, Washington, D. C.

Application May 24, 1945, Serial No. 119,694

Term of patent 7 years

(Cl. D83—1)

To all whom it may concern:

Be it known that I, Frederick Fink, a citizen of the United States and an officer in the United States Army, have invented a new, original, and ornamental Design for a Crutch Grip, of which the following is a specification, reference being had to the accompanying drawing, forming part thereof.

Fig. 1 is a side elevational view of a crutch grip showing my new design;

Fig. 2 is a side perspective view thereof;
Fig. 3 is a top plan view thereof; and
Fig. 4 is an end elevational view thereof taken from the left of the device in Fig. 3.

I claim:

The ornamental design for a crutch grip, as shown.

FREDERICK FINK.
